FACSIMILE PRINTER BLADE ASSEMBLY

Nathaniel L. Cohen, New Milford, and Joseph J. Turano, Rego Park, N. Y., assignors to Air Associates, Inc., Orange, N. J., a corporation of New Jersey

Application May 31, 1955, Serial No. 511,939

1 Claim. (Cl. 346—139)

The present invention relates in general to facsimile recorders of the type employing the so-called "lawnmower" electrode system in which an electro-sensitive recording medium is passed between a substantially stationary linear electrode or printer blade and a cooperating rotating helical electrode for purposes of effecting marking of the recording medium in response to signal intelligence transmitted to the electrode system from a suitable facsimile scanner. More particularly, the invention contemplates the provision of an improved stationary electrode or printer blade and printer blade assembly for use in recorders of the general class described as well as improved methods for mounting the printer blade in operative relationship with respect to the cooperating helical electrode.

Fundamentally, the theory of operation of facsimile transmission and recording as well as duplication processes employing facsimile principles, involves the translation of subject intelligence from an original copy sheet into electrical currents characteristic of contrasting areas of the original copy and effected by impinging light from successive small areas of the copy onto a photoelectrically responsive device provided at the facsimile transmitter. At the receiving or reproduction end of the system, the characteristic currents are used to control means for reproducing the original image or intelligence, which, in the "lawnmower" type of recorder, is accomplished by drawing an electrically sensitive sheet or carrier across the rotating helical electrode and under the intersecting stationary linear electrode. The intersection of the two electrodes forms a linear scanning area which owing to the helical form of the rotating electrode moves across the paper from side to side while a steady forward movement of the recording medium between the electrodes completes the scanning motion. The variable density markings of the original copy are reproduced by passing the characteristic currents generated at the transmitter between the linear and helical electrodes and through the electrically sensitive recording sheet passing therebetween.

The phenomena of marking or recording in most facsimile systems is electrolytic in action and the density and intensity of the marks produced on the recording sheet, among other factors, depend upon the nature of chemical reactions occurring within or upon the recording sheet during electrolysis. Certain known sensitizing agents used in electro-chemical wet recording papers for instance, are known to be more stable when in an acid condition. Owing to the corrosive action of electro-sensitizing agents of this type as used in the manufacture of some facsimile papers as well as the general electrolytic action which occurs during recordation in all electro-chemical wet recording systems, it is found that the linear electrode or printer blade used to effect marking of the recording paper becomes pitted and must be replaced as a standard maintenance procedure. In fact, in one form of recording paper now employed by industry, the printer blade actually constitutes the source of one component of the electro-chemical marking reaction, in that

2

it functions to supply lake-forming metal ions to the reaction for the formation of colored dyes, with the result that the printer blade is virtually consumed in a relatively short time and requires relatively frequent replacement. Accordingly, it is essential in recording mechanisms of the general class described that the printer blade be relatively simple in design and production cost and that the blade be assembled or positioned within the recorder in such manner as to permit ready access 10 for cleaning and replacement by unskilled persons, such, for example, as clerical personnel within an office or similar business establishment.

Apart from replacement considerations etc., it is essential to proper functioning of a recorder that the printer 15 blade be sufficiently rigid to insure good conductive contact with respect to the recording medium and helical electrode while at the same time it must also be sufficiently flexible in a linear direction and in a direction substantially tangential to the surface of the recording 20 drum to permit mounting of the blade onto the raised helix and descent from the helix for each revolution of the drum without undue drag or wrinkling of the recording paper. In the past, these physical requirements have been obtained or sought through rather elaborate and 25 expensive printer blade designs with the result that the aforementioned replacement considerations involve a relatively costly maintenance factor. In addition, the very complexity of known blade designs introduces a potential source of operating difficulties which customarily require the attention of a skilled technician for correction or elimination.

It is the principal object of the present invention to provide a facsimile printer blade of extremely simple and inexpensive construction that includes within an 30 otherwise unitary blade structure, two separate and completely interchangeable printing surfaces.

It is a further object of the invention to provide a printer blade assembly for use on a facsimile recorder in which the printer blade is so positioned as to provide 35 for ready accessibility for removal and replacement by even unskilled persons.

A still further object of the invention is the provision 40 of an adjustable facsimile printer blade mounting or holder which is so designed as to automatically insure a proper degree of resiliency to an expendable or replaceable printer blade unit used in conjunction therewith.

The above-mentioned and other features and objects of the invention and the manner of attaining them will 45 become more apparent and the invention itself will be best understood by reference to the following description of a specific embodiment of the invention taken in conjunction with the accompanying drawings, wherein:

Fig. 1 is a perspective view showing the linear electrode or printer blade of the invention disassociated from the 50 blade holder or mounting bracket;

Fig. 2 is a plan view of the complete printer blade assembly with the linear electrode element or printer blade of Fig. 1 in an operative position within the blade holder or mounting;

Fig. 3 is an elevational view of the printer blade assembly as illustrated in Fig. 2;

Fig. 4 is a cross-sectional view of the printer blade assembly taken along the line 4—4 of Fig. 2, showing the relative positioning and mounting arrangement of 55 the removable printer blade within the blade holder;

Fig. 5 is a cross-sectional view of the printer blade assembly taken along line 5—5 of Fig. 2, showing the tensioning arrangement employed in the blade assembly of the invention; and

Fig. 6 is a fragmentary end view of a facsimile recorder showing the printer blade assembly of the invention in

operative relationship with respect to a recording drum and the helical electrode carried thereon.

With reference to Fig. 1 of the drawing, there is illustrated in perspective, the removable and replaceable linear electrode element or printer blade 10 of the invention which consists of a simple thin metallic strip bent at each edge to form a substantially S-shaped unit providing two separate and interchangeable electrode surfaces 11. The printer blade 10 may be formed of any suitable conductive material but in practice we have found that a relatively inert alloy of steel, such, for example, as "Carpenter steel," is preferred from the standpoint of durability. Of course, when the printer blade is employed in conjunction with specific electro-sensitizing agents, the actual electrode surfaces or edges of the blade may be plated or coated with any suitable metallic substance or alloy to provide for increased resistance against corrosion and electrolytic decomposition or to provide a source of reactive material necessary to the electrochemical marking phenomenon.

With reference to Figs. 2 and 3 of the drawings, the printer blade mounting assembly of the invention consists of an elongated metallic frame or channel member 12 closed on three sides and having mounted thereon at each end by means of retaining bolts 13, a blade-retainer piece 14. As best seen by reference to Fig. 4, the metallic frame 12 and blade-retainer pieces 14 mounted at each end thereof, define two substantially closed channel sections into which printer blade 10 is received by sliding from a single substantially open end provided at one end of the frame. Thus, one end (upper end Figs. 2 and 3) of frame 12 is provided with a relatively extended stop abutment piece 15 which is adapted to contact the end of the printer blade when it is fully received within the frame to prevent any movement of the blade beyond this end of the frame, whereas at the opposite end of frame 12 (lower end Figs. 2 and 3) a relatively low abutment or lip 16 is formed integral with the frame and is adapted to permit insertion of the blade by simply sliding it over the lip until the blade is fully inserted in the frame at which point the edge of the blade drops below the lip thereby securing the blade against movement in either direction within the frame during the printing operation. To remove a blade for reversal of its electrode edges or complete replacement, it is simply necessary to lift the end of the blade slightly to clear abutment 16 and then slide the blade out over the abutment.

Again with reference to Fig. 4, it will be seen that printer blade 10 is retained within the channel sections formed by frame 12 and blade-retainer pieces 14 in a freely pivotal position for movement about the fulcrum point indicated by reference numeral 17 in Fig. 4. Accordingly, any force applied against the operative electrode surface of the blade, such as that encountered when the blade rises and falls from the helical electrode at the beginning and end of each revolution of the recorder drum, will be absorbed by a simple pivotal motion of the blade within the frame. In order to insure good conductive contact at all times, the aforescribed motion of the linear electrode is resiliently restrained by means of a butterfly spring 18 (Fig. 5) which is centrally anchored on frame 12 by means of nut and bolt assembly 19. Spring 18 is provided with a clip extension 20 at the end of each leaf thereof which are adapted to engage the forward angled edge of printer blade 10 thereby tensioning the blade both inwardly and downwardly. Upon removing a blade, the clip extensions 20 are simply lifted out from the edge of the blade and permitted to extend freely below the bottom of frame 12 until a blade is reinserted in the frame and the clips are then repositioned thereon, as best seen by reference to Fig. 5.

At the ends of frame 12 and also secured to the frame by retaining bolts 13, we provide a pair of channel blocks 21 for mounting the printer blade assembly within a facsimile recorder. With reference to Fig. 6 of the draw-

ings, channel blocks 21 are adapted to be received within channels 22 provided in a pair of rocker arms 23 pivotally suspended from each side of the recorder in the manner described in our copending United States application Serial No. 569,868 which was filed on March 6, 1956, entitled "Facsimile Recorder." Channel blocks 21 are each provided with a seating hole 24 which is adapted to receive a tensioning spring 25. Below the spring seatings 24, the channel blocks 21 are tapped as indicated by reference numeral 26 in Fig. 6 to engage a knurled adjustment bolt 27 which extends through holes 28 provided in the rocker arms 23. In this manner, the positioning and pressure of the printer blade with respect to the record sheet and helical electrode 29 can be adjusted by a simple adjustment of bolts 27 while the machine is in operation, thereby insuring optimum quality of copy under various operating conditions.

Referring to Fig. 6, reference numeral 30 represents a recording drum carrying the conventional helical electrode 29. In order to avoid strain on printer blade 10 resulting from tension within the recording paper, which has been indicated by reference numeral 31 in Fig. 6, and to insure that the paper is presented to the electrode system (10-29) in a plane substantially perpendicular to the current path through the electrodes, we provide a paper guide strip 32 on frame 12. Paper guide 32, which may be formed of any suitable non-conductive material, is riveted or otherwise secured to frame 12 and extends completely across the frame as best seen by reference to Fig. 2.

As the paper is fed under the opposed electrodes, paper guide 32 serves to absorb any shock or tension within the paper that might otherwise result in fluttering or vibration of the linear electrode 10 and also positions the paper tangentially to the surface of recorder drum 30 and helical electrode 29 carried thereon. The guide is adjustably positioned by the same adjustment bolts 27 which control the positioning or pressure of printer blade 10.

Any suitable connection can be used to complete the electrical circuit from the helical electrode, such, for example, as a wire lead soldered to frame 12 or secured thereto with a conventional lug connector at nut and bolt assembly 19.

While we have described above the principles of our invention in connection with a specific embodiment thereof, it is to be clearly understood that this description is made only by way of illustration and not as any limitation with respect to the scope of our invention as defined within the following claim.

We claim:

In a facsimile recorder of the type employing a substantially stationary linear electrode and a cooperating rotating helical electrode carried on a cylindrical recorder drum, a linear electrode assembly comprising a removable printer blade having two identical linear electrode surfaces formed thereon which are selectively engageable with the helical electrode, a supporting frame for said printer blade electrode including means for pivotally securing said blade therein, means mounted on said frame and positioned to engage said printer blade for resiliently tensioning the blade against pivotal motion within said frame, and a paper guide element secured to said supporting frame immediately adjacent said printer blade and positioned to guide a facsimile recording sheet into contact with an electrode surface of said printer blade in a plane tangential to the surface of the cylindrical recorder drum carrying the helical electrode.
